CLAIM

The ornamental design for a tire, as shown and described.

DESCRIPTION

FIG. 1 is a perspective view of a tire showing the new design.

FIG. 2 is a front view thereof. The top and bottom views thereof are identical to the front view.

FIG. 3 is a rear view thereof.

FIG. 4 is a left side view thereof. The right side view thereof is a mirror image of the left side view; and,

FIG. 5 is a detail view from upper 5-5 to lower 5-5 of FIG. 2.

The broken lines illustrate environmental subject matter only and form no part of the claimed design. The dot-dash-dot line illustrates a boundary of the claim and itself forms no part thereof.
